UNITED STATES PATENT OFFICE.

WILLIAM H. MUZZY, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CASH-REGISTER.

1,015,825.

Specification of Letters Patent. Patented Jan. 30, 1912.

Application filed January 10, 1908. Serial No. 410,142.

To all whom it may concern:

Be it known that I, WILLIAM H. MUZZY, a citizen of the United States, residing at Dayton, in the county of Montgomery and State of Ohio, have invented certain new and useful Improvements in Cash-Registers, of which I declare the following to be a full, clear, and exact description.

This invention relates to improvements in cash registers and has more particular relation to improvements in registers of the multiple drawer type for use by a number of clerks keeping independent accounts.

The particular object of the invention is to provide a register of the type mentioned, so constructed that it will accomplish the desired results at a minimum cost and with a very simple operation.

A further object of the invention is to provide a plurality of multiple drawers or receptacles, and a suitable simple checking means whereby the amounts of sales of different clerks can be readily ascertained and checked in connection with the cash in the cash drawers.

With these and incidental objects in view, the invention consists in certain novel features of construction and combination of parts, the essential elements of which are set forth in appended claims and a preferred form of embodiment of which is hereinafter specifically described with reference to the drawings which accompany and form part of this specification.

Of said drawings: Figure 1 represents a perspective view of a machine embodying my invention, arranged for three clerks; Fig. 2 represents a vertical transverse section through the same; Fig. 3 represents a detail perspective view of one of the drawer latches, its shaft, bell trip, etc.; Fig. 4 represents a plan view of one of the checks; and Fig. 5 represents a detail side elevation of one of the cover latches.

Described in general terms, the invention may be said to comprise a plurality of check receptacles arranged to feed checks of different denominations, and each of which is provided with a cover for protecting or guarding said checks. A series of cash receptacles are also provided together with

connecting mechanism, whereby when any one of the covers is raised to permit access to the series of checks beneath it, the corresponding cash drawer is released and a corresponding signal brought into operation.

The base portion 1 of the machine is provided with three sliding cash drawers 2 suitably mounted in said base so as to be automatically projected therefrom by springs 3 when released, in a manner well known in the art. Each of the drawers is normally held within the casing by drawer latch 4 which engages a bevel hook 5 secured to its rear wall. Each of the latches 4 is pivoted upon a transverse shaft 6, which is mounted in the base, and is normally held up into operative position by one end of a coil spring 7 which surrounds said shaft and bears with its opposite end against the rear wall of the casing 1.

The shaft 6 is provided near one end with an arm 8 carrying a stud 9 which projects into an elongated slot 10 formed in the lower end of a link 11. The upper end of this link, as best shown in Fig. 5, is provided with a stud 12, which projects through an eccentric slot 13 formed in a disk 14 which is fast to the journal pin 15 of one of the covers 16 for the check receptacles. The formation of the eccentric slot 13 is such that when the cover 16 is opened or raised, the link 11 will be forced downward and will thus cause latch 4 to disengage from hook 5 and release the corresponding cash drawer. After the cover 16 is closed the drawer can again be re-latched by the bevel hook 5, forcing the latch 4 downward against the tension of its spring 7. Each disk 14 is provided with two V notches (16^a and 17) into which a spring pressed plunger 18 mounted in a casing 19 is adapted to project to hold the cover 16 in its adjusted positions. Each of these covers 16 normally covers or guards the upper ends of vertical check receptacles 20, each of which is provided with a transparent front wall 21 and a false bottom 22 mounted upon a vertically guided slide 23. This slide is normally forced upward by coil springs 24, which connect it to the walls of the check receptacle. The checks are limited in their

ward movement under the impulse of the bottom 22 by lugs 24 which project over their rear ends at the top. The checks 25 are printed with suitable advertisements, 5 rebate information, a consecutive number, and in large type the amount which is represented by the check.

In Fig. 1 it will be seen that each clerk is provided with a series of checks representing respectively 10, 25, 35, 50 and 60 cents. This arrangement of checks is particularly useful in barber shops, soda fountains, cigar stores and the like, where the amounts of the sales are very low. Whenever the checks in any particular receptacle are exhausted, this fact becomes at once apparent by glancing through the transparent wall 21. Each of the shafts 6 is also provided with a bell trip 30 loose on the shaft 20 and formed with a recess 31, into which projects a pin 32 projected radially from the shaft. A coil spring 33, having one end secured to the shaft, forces the trip 30 normally rearward, as shown in Fig. 3. This trip 30 cooperates with a pivoted pawl 34 mounted on a lever 35, and limited in its movement by a lug 36. The lever 35 is pivoted on the rear wall of casing 1, and is provided with a stop projection 37 and a bell hammer 38, which is arranged to strike a bell 39, suitably mounted in the casing.

From the above description it will be seen that when any one of the covers 16 is opened, it will be held in its open position by its plunger 18. This opening movement of the cover will also release the corresponding cash drawer and sound the corresponding bell; these bells being of different tones so as to be readily distinguished. After the cover 16 is opened, the clerk removes a check representing the amount of the sale, then closes the cover again, and after making the proper change, finally closes his cash drawer and hands the check to the customer as his receipt and to retain for rebates. One clerk cannot interfere or tamper with the checks belonging to any other clerk, or gain access to another clerk's cash drawer without ringing the bell, which would inform the clerk 45 that some unauthorized person was entering his cash drawer and check compartments.

After the day's business is over, the contents of the several cash drawers are counted, and these amounts checked against the 55 checks which have been removed from the different check receptacles. For instance, each set of checks, as before stated, is consecutively numbered, and before starting business in the morning, the proprietor takes 60 the consecutive number of the different checks of the several clerks in the following manner: Clerk A 10¢. check No. 45; 25¢. check No. 30, etc. At the end of the day's business, by comparing the consecutive numbers 85 of the remaining checks, he can readily

see just how many checks have been given out from each compartment, and by multiplying this number by the amount of the checks, he can quickly ascertain how much cash should be found in each cash drawer. 70 By this means he has a complete check upon the amounts of the different transactions and the accounts of the several clerks are kept altogether separate.

It will, of course, be understood that any 75 desired form of signal or cash receptacle can be employed in connection with the check receptacle, it only being necessary that access to the checks is prevented until the covers have been opened sufficiently to release 80 the cash receptacle and bring the signal into operation.

While the form of device here shown and described is admirably adapted to fulfil the objects primarily stated, it is to be understood that it is not desired to confine the invention to one form of embodiment here disclosed, for it is susceptible of embodiment in various forms, all coming within the scope 90 of the claims which follow.

What is claimed is:

1. In a cash register, the combination with a series of cash receptacles, of a series of corresponding check receptacles, covers for said check receptacles, a series of signals, and means for releasing the proper cash receptacle and operating the proper signal upon the opening of the corresponding check receptacles.

2. In a cash register, the combination with a series of cash receptacles, means for feeding the checks in said receptacles, covers for said receptacles, and means for releasing the cash receptacles controlled by the covers of the check receptacles.

3. In a cash register, the combination with a series of cash receptacles, of a series of check receptacles, pivoted covers for said check receptacles, latches for the cash receptacles, and means for operating the latches from the pivoted covers.

4. In a cash register, the combination with a series of cash receptacles, of a series of check receptacles, covers for the check receptacles, means for releasing the check receptacles by the movements of said covers, and means for holding the covers in their adjusted positions.

5. In a cash register, the combination with a series of cash drawers, of a series of check receptacles, means for feeding checks in said receptacles, covers for the check receptacles, latches for the cash drawers, means for operating the latches upon the opening of the covers, and different signals operated according to the cash drawer opened.

6. In a cash register, the combination with a series of cash drawers, of a series of check receptacles, means for feeding the checks in said receptacles, covers for the check recep-

tacles, and latches for the cash drawers arranged to be operated by said covers.

7. In a cash register, the combination with a plurality of cash drawers, of a plurality of check receptacles, means for feeding checks in said receptacles, covers for the said receptacles, a plurality of alarms, and means for releasing a particular cash drawer

and sounding its alarm upon the opening of the corresponding check receptacle cover. 10

In testimony whereof I affix my signature in the presence of two witnesses.

WILLIAM H. MUZZY.
